UNITED STATES PATENT OFFICE

2,512,759

DEVICE TO FACILITATE THE REMOVAL OF
ICE TRAYS

William M. Allen, Glendale, and Robert A. Anderson, Hamilton, Ohio, assignors to Model Crafters Inc., Hamilton, Ohio, a corporation of Ohio

Application February 26, 1947, Serial No. 731,156

3 Claims. (Cl. 62—1)

1

This invention relates to a device to facilitate the removal of ice cube trays from the shelves of a refrigerator evaporator.

Most modern refrigerators are provided with an evaporator or freezing unit having a compartment with shelves therein. The walls of the evaporator and usually also the shelves contain or have associated with them conduits for refrigerant. Ice cube trays are placed on these shelves having previously been filled with water and contain dividers for the purpose of producing ice cubes.

Usually the ice cubes are not used as soon as they are frozen and the longer an ice cube tray remains in the evaporator the more tightly the tray tends to freeze to the shelf on which it rests.

Various means and procedures have been used heretofore to assist in breaking the ice cube tray loose from its shelf, but in the absence of some sort of built in freeing device the average housewife will use a screw driver or a can opener or the like with attendant damage to the evaporator or trays.

It is an object of our invention to provide an accessory which can be used with existing units which will eliminate damage to the evaporator or trays and which will greatly facilitate the removal of an ice cube tray from the evaporator. It is another object of our invention to provide a device as outlined above which will tend to prevent the ice cube tray from freezing to the shelf. Further objects of our invention include the provision of such a device which is extremely simple and inexpensive in construction and fool proof in operation.

These and other objects of our invention which will be pointed out in more detail hereinafter or which will be apparent to one skilled in the art upon reading these specifications, we accomplish by that certain construction and arrangement of parts of which we shall now describe certain exemplary embodiments.

Reference is made to the drawings forming a part hereof and in which:

Fig. 1 is a side elevation of our device in one of its forms.

Fig. 2 is a plan view of the same.

Fig. 3 is a cross sectional view on a greatly enlarged scale taken on the line 3—3 of Fig. 2.

Fig. 4 is a fragmentary plan view showing a modified form of the device.

Fig. 5 is a fragmentary plan view showing a modified handle structure.

Fig. 6 is a fragmentary plan view of a modified form of our invention.

2

Fig. 7 is a cross sectional view taken on the line 7—7 of Fig. 6.

Briefly in the practice of our invention we provide an element adapted to rest upon the shelf of a refrigerator evaporator upon which an ice cube tray can be supported in spaced relation to said shelf. The element is so constructed that it will have substantially line contact with the shelf to minimize the surface in contact and therefore to minimize the tendency of the parts to freeze together, and it will preferably be coated with a freezing inhibiting paint.

The preferred form of our device, as shown in Figs. 1 and 2, comprises a substantially rectangular loop of wire having the long sides 10 and 11 and the short sides 12 and 13. The ends of the wire are brought together within a sleeve 14, as clearly shown in Fig. 2. The end of the loop adjacent the sleeve 14 is bent up as at 15 to provide a handle portion.

We have found that if the ice cube tray is supported at too great a distance from the evaporator shelf, ice will not be formed in the tray as rapidly as might be desired, and we therefore prefer to use wire of a thickness on the order of $\frac{1}{16}$ inch. This appears to us to be a very satisfactory compromise between too great an increase in freezing time and too great a tendency for the parts to freeze together. With a wire of a thickness of about $\frac{1}{16}$ inch, the device will have substantially line contact with the shelf and any freezing which takes place between the parts will be along a thin line which can readily be broken loose. In order to further fulfill the objects of our invention, we prefer to coat the wire, as for example, by dipping or spraying and then baking, with a freezing inhibiting paint. Such paint should be able to withstand low temperatures and be resistant to abrasion. We prefer to use a plastic paint, such as is commercially available under the name "Amercoat" manufactured by American Pipe and Construction Co. This is a plastic paint whose main constituent is vinyl plastic. The wire itself can be of any kind having sufficient strength, and we prefer to use wire of characteristics similar to that used in coat hangers.

The sleeve 14 is preferably made from extruded plastic tubing and may have an outside diameter, for example, of $\frac{3}{16}$ inch.

The loop is made of such dimensions that it is universal in its application. We have found that if the wire loop is approximately 2 inches by 8 inches, even the smallest ice cube tray now on the market will fit on it.

In use the device is placed on the shelf of the evaporator and the ice cube tray is placed on the device, as shown in Fig. 1. By virtue of the upwardly bent configuration 15, the sleeve or handle portion 14 will be adjacent the handle portion 16 of the ice cube tray 17, so that both may be grasped at the same time. With a device as described above, a very slight pull will serve to break the tray loose from the shelf.

In Fig. 3 the wire is indicated at 18 and the 10 coating of the freezing inhibiting paint is indicated at 19.

In Fig. 4 we have shown a modification in which the end 12 of the wire loop is rounded as at 12a, and in Fig. 5, we have shown a modification of the handle portion where the ends of the wires, after having been bent up as at 15a, are lapped as at 19 and 20. These portions 19 and 20 may then be soldered or welded together. In this modification we do not use the plastic sleeve 14, but we coat the portions 19 and 20 with the same freezing inhibiting paint.

In Figs. 6 and 7, we have shown a further modification in which, instead of a wire, we use a flat strip of sheet metal 21, provided with an upstanding central rib 22. The rib 22 has the same function as the wire in the embodiment of Figs. 1 and 2 in that it provides substantially line contact with the refrigerator shelf. While we have shown this embodiment with the rib 22 disposed downwardly to contact the shelf, it could also be disposed upwardly so as to contact the tray. In any event with this embodiment there may be a tendency for the flat surface to adhere to the shelf or tray, depending upon whether the rib extends upwardly or downwardly respectively, but in either case the freezing contact between the rib and the other of the two surfaces can be easily broken.

The embodiment of Figs. 6 and 7 will also be coated with a freezing inhibiting paint as described above.

While we have shown the device as a separate article, it will of course be understood that it may be made a part of either the tray or the shelf by being welded or otherwise suitably fastened thereto. In such case the handle portion could conveniently be omitted, and the device would comprise simply a pair of coated wire runners, a coated wire loop or other suitable configuration.

It is also worthy of mention that the coated

wire we use can be readily bent without deleteriously affecting the coating. Thus, if perchance the loop of one of our devices should be too long or too narrow for a particular use, it may easily be bent by hand to the desired shape.

It will be clear that numerous modifications may be made without departing from the spirit of our invention and we therefore do not intend to limit ourselves, except as pointed out in the claims which follow.

Having now fully described our invention what we claim as new and desire to secure by Letters Patent is:

1. A device of the class set forth, comprising an element adapted to rest upon the shelf of a refrigerator evaporator, and to support an ice cube tray in spaced relation to said shelf, said element having substantially line contact with one at least of the surfaces of said shelf and said tray, said element comprising a rectangular metal loop member, the ends of said metal loop member being axially aligned in a short side of a rectangle and being enclosed in a tube of thermally non-conductive material, the ends of said metal loop member adjacent said tube being bent upwardly to form a handle member, and said metal loop member being coated with a freezing inhibiting paint.

2. A device according to claim 1 in which said rectangular metal loop member is constituted of a strip of sheet metal having a substantially central stiffening rib of narrow cross section.

3. A device according to claim 1 in which said rectangular metal loop member is constituted of a length of wire.
